Webster & Co.,
ATTORNEY S.

UNITED STATES PATENT OFFICE.

THOMAS THOIN, OF WEST SPRINGFIELD, MASSACHUSETTS.

AMUSEMENT DEVICE.

1,096,474.

Specification of Letters Patent.

Patented May 12, 1914.

Application filed August 4, 1913. Serial No. 782,769.

To all whom it may concern:

Be it known that I, THOMAS THOIN, a citizen of the United States of America, residing at West Springfield, in the county of 5 Hampden and State of Massachusetts, have invented a new and useful Amusement Device, of which the following is a specification.

My invention relates to that type of an 10 amusement device known as a target device, and more especially to a device designed to serve as a target for balls thrown by hand, and said invention consists essentially of a revoluble member equipped with certain pec- 15 culiar, peripheral, rotatable, target members, together with such subsidiary and auxiliary parts and members as may be found desirable or necessary for use in connection with said first-mentioned members, all as 20 hereinafter set forth.

The object of my invention is to produce a comparatively simple and inexpensive device which is capable of presenting to the marksman, that is, to the person throwing 25 the ball or balls, a plurality of moving targets, which targets have independent movements when struck and are caused to be changed by the force of the blow. In this device the targets have what may be called 30 a normal or constant motion, and they are also capable of an independent movement, the latter being at right-angles to the former, and the targets all moving together in the first instance and only as individuals or 35 individual groups in the second instance.

Other objects and advantages will appear in the course of the following description.

I attain the objects and secure the advantages of my invention by the means illus- 40 trated in the accompanying drawings, in which—

Figure 1 is a front elevation of a device which embodies a practical form of my invention, the upper portion of the back screen 45 being broken off, and a portion of the front screen being broken out in order fully to disclose one of the target units; Fig. 2, a side elevation of the parts shown in the first view, and, Fig. 3, an enlarged detail in sec- 50 tion of one of the target-unit stops or checks.

Similar figures refer to similar parts throughout the several views.

I prefer to use in connection with my amusement device front and back screens 1 55 and 2, respectively. These screens may be made of any suitable material and support-

ed in any suitable manner, but in the present case I employ a suitably constructed frame 3 to the front of which the screen 1 is attached, and a suitably constructed frame 4 to the front of which the screen 2 is attached. The frames 3 and 4 also serve to support a shaft 5 which constitutes a part of the amusement device proper. 60

The screen 1 may extend upward to a level 65 with the axis of any one of the target units, presently to be described, when such unit is in its highest position, as shown, or said screen may be low enough to expose more of the targets, as may be desired. Obviously no part of the device which is below 70 the top of the screen 1 can be struck by a ball thrown at the device. Thus it is seen that the screen 1 hides and protects everything that it is not desired to have exposed 75 to the balls thrown at the device.

In practice the screen 2 must extend high 80 enough to intercept all balls thrown over the top of the screen 1, whether such balls strike an exposed target or not. It is not necessary, of course, for the screen 2 to extend clear to the ground or even very far below the horizontal plane of the top of the screen 1.

Securely mounted on the shaft 5 is a rotary member 6 which may be in the form of a wheel or disk of any suitable construction. The member or disk 6 carries on its periphery a series of rotatable target units 7. Each unit 7 is in the form of a four-bladed 85 paddle-wheel, and includes an axial member 90 which in the present case consists of a sleeve 8 from which the blades extend.

Combined with each unit 7 is some suitable supporting means for said unit, which 95 means may consist of a U-shaped support 9 having its inner ends rigidly attached to the disk 6, and upon the cross-piece of which support is mounted the sleeve 8 of such unit. Each unit 7 is retained by its support 9 far 100 enough beyond the periphery of the disk 6 to clear said disk when said unit is rotated, and the direction of rotation of said unit is necessarily at right-angles to that of said disk. 105

On the face of each blade of each unit, which is presented to the front and above or beyond the unit sleeve 8 when such face is vertical, may be delineated or affixed a picture as shown, or some other character, 110 figure, marking, or designation. The designations thus employed can be arranged in

series or otherwise as may be found expedient. In some cases, however, the units 7 may be left entirely plain or blank.

The member or disk 6 is mounted on the 5 shaft 5 between the screens 1 and 2, and said shaft and supported parts are revolved by any suitable means and in any suitable manner, a crank 10 on the rear end of such shaft being the means herein provided, inasmuch 10 as it is intended to operate this device by hand.

For the purpose of checking the rotary motion imparted to any one of the units 7 by the blow from a ball, so that such unit 15 shall come to rest with two of its oppositely disposed blades or arms in a vertical position, I may provide said unit with recessed end plates 11, and spring-pressed pins 12 to operate in connection with said plates. 20 Each plate 11 is rigidly attached to one of the units 7 at one end, and such plate has a recess 13 in the outer face thereof directly in line with each unit blade. The cross-piece of each support 9 is provided, adjacent to the plate 11 mounted with the sleeve 8 thereon, with a holder 14 which is recessed to receive one of the pins 12 and a spring 15, the latter being introduced between the inner end of the pin and the closed 25 end of the recess. The pin 12 thus slidingly mounted in the holder 14 is thrust against the adjacent plate 11 by the spring 15, and is arranged in the circular path of the recesses 13 in said plate. The end of the pin 30 12 which protrudes from the holder 14 is rounded, and the recesses 13 are made concave and are elongated in the direction of their rotation or path, so that said bolt can enter and leave said recesses freely. 35

40 From the foregoing it is clear that the pins 12 exert an influence over the unit 7 in retaining them in their normal and stationary condition or position on the supports 9, and have a tendency to check said units when independently rotated and finally to stop them in the desired position.

In practice, the shaft 5 is revolved by means of the crank 10 at whatever rate of speed may be desired, with the result that 50 one unit blade and its picture after another are presented to view above the top of the screen 1. Balls are thrown at these exposed blades, and whenever one is hit the unit which comprises it is caused to rotate 55 and continues so to do until again brought to rest by the contacting pin 12. The amount of rotation imparted to the unit struck by a ball depends upon the force be-

hind the ball, but usually the momentum thus imparted to the unit is not sufficient, 60 or at least it may not be sufficient, to cause said unit to make more than a part of a revolution. This naturally depends on the strength of the spring 15 and the force of the blow. Unless a unit when struck makes 65 one complete revolution, a new picture is brought into view to receive the next blow.

It is apparent that this device without material change can be utilized for playing games of various sorts. 70

Various changes in the shape, size, construction, and arrangement of some or all of the parts of the device, as herein shown and described, may be made without departing from the nature of my invention. 75

What I claim as my invention, and desire to secure by Letters Patent, is—

1. The combination, in an amusement device, with a rotary member, and a series of target units mounted for complete rotation 80 on the periphery of said member in a direction at right-angles to the direction of rotation of said member, each of such units comprising a plurality of blades arranged radially to a common axis and of uniform 85 size and shape, of means to check each of said units and retain it with any blade in normal position.

2. The combination, in an amusement device, with a revolute member, and a series 90 of supports attached to said member, said supports being provided with yielding pins, of a series of target units mounted on said supports and adapted to be rotated thereon, said units each comprising a plurality of 95 blades and being provided with a recessed member for engagement with the associated pin.

3. The combination, in an amusement device with a rotary member, and a series of 100 target units mounted for complete revolution on the periphery of said member in a direction at right-angles to the direction of rotation of said member, each of said units comprising a plurality of blades arranged 105 radially to a common axis, of uniform size and shape, and having designations on the faces of such blades which are designed to be exposed as targets, of means to check such unit and so retain it as to present the 110 designation on any blade thereof in normal position.

THOMAS THOIN.
